UNITED STATES PATENT OFFICE.

JOHN CARLISLE POMEROY MAGWOOD, OF LONDON, ENGLAND.

APPARATUS FOR PLAYING RACE GAMES.

Application filed June 18, 1923. Serial No. 646,207.

To all whom it may concern:

Be it known that I, JOHN CARLISLE POMEROY MAGWOOD, student, a subject of the King of Great Britain, residing at 5 146 Adelaide Road, Hampstead, London, England, have invented certain new and useful Improvements in Apparatus for Playing Race Games, of which the following is a specification.

10 This invention refers to apparatus for playing a race game wherein toy figures or models of horses or other things (all of which for convenience, are hereinafter referred to as "the pieces") are caused to travel from end to end of a substantially straight course, means being provided to vary the order of finishing according to chance.

15 An object of this invention is to reproduce mechanically in as life-like a manner as possible the progress of an actual race, and a further object is to introduce a mechanical chance element or elements the nature and operation of which are such as to 20 present a continually changing combination operative against the several "pieces," in suchwise that the players cannot become aware, before, and in many cases even during the earlier part of a race, of the winning 25 "piece."

Apparatus according to the present invention, therefore, comprises in combination with a suitable board or platform forming the course for the "pieces," means for imparting movement to the latter, and mechanically operated means which may or may not, according to chance, interrupt the progress of the individual "pieces" at one or more points in their travel.

30 The accompanying drawings illustrate, by way of example only, one constructional embodiment of my present invention.

In these drawings:—

Fig. 1 is a plan view of the apparatus 35 with part of the box cover or top removed.

Fig. 2 is a side view with the side of the box or case removed.

Fig. 3 is a side view on an enlarged scale 40 of a detail, viz. the driving means for the endless band hereinafter described.

Fig. 4 shows a longitudinal section of one suitable construction of the carriers for the "pieces."

Fig. 5 is an end view of such carrier.

55 Figs. 6 and 7 show respectively a longi-

tudinal section and an end view of an alternative construction of carrier.

Fig. 8 is a side view.

Fig. 9 a cross-section, and

Fig. 10 a plan view of a guide (for the 60 endless band) which guides may be used in place of the drums or pulleys shown in Figs. 1 and 2.

Referring to these drawings:—

A represents a box or case of wood or 65 metal or other suitable material the top of which is provided with longitudinally disposed parallel slots B, one for each "piece," in this case four.

Under each slot B is mounted a screw-threaded spindle C rotatable in bearing plates D and E, the said spindles having mounted at one end thereof meshing toothed wheels C'. One spindle projects through the end of the box A and is provided with 70 a crank F, by means of which said spindles are driven, the screw threads thereon being alternately right hand and left hand screws. These screw threads of the required pitch may be easily and cheaply applied to the 75 spindles, by winding on a mandril, the predetermined length of wire in the form of a close coil, which is threaded over the spindle and the ends of the coil then drawn apart. The ends may then be soldered to the spindle if desired.

80 The driving spindle is also provided with a toothed wheel G advantageously mutilated as shown, i. e., with teeth over a portion only of its periphery, and these teeth are adapted 85 to engage a crown wheel H to which is fixedly attached a sprocket J, the whole being rotatively mounted in a fixed bracket K (see particularly Fig. 3).

An endless band L of thin steel, or other 90 suitable material, e. g., phosphor bronze or celluloid is punched over its whole length to the pitch of the sprocket teeth, and runs over rotative pulleys or drums M (one of which may be adjustable) attached to the 95 bottom of the box.

The upper edge of the said band L is recessed or cut away at intervals, preferably irregular intervals, and the said recesses themselves are advantageously of various 100 lengths.

A carrier N provided with pins N' for carrying the "piece" O is mounted on each spindle C, and is provided with a depending 105 pivoted stirrup P held against rearward 110

2 pivoting movement by a pin or abutment Q, but free to pivot forwardly to allow unobstructed return of the carrier to starting position.

- 5 To the bottom of stirrup P is fixed a stud P¹ the position of which in relation to the endless band L is such that the stud P¹ will pass freely through the recesses, but will engage the solid or uncut portions of the band 10 L, during forward movement of the carrier N.

In Figs. 4 and 5 I have shown a suitable carrier which may be stamped from sheet metal. The downwardly bent lugs N² engage the threads of spindles C to ensure positive drive of the carriers until the latter are obstructed by solid portions of the band L whereupon the carriers will ride over the screw threads producing an imitation of 20 the galloping movement of a horse. The upturned ends N³ of carriers N are provided to contact with the underside of the top of the box when the carriers are lifted clear of the spindles C to return the "pieces" 25 to starting position.

In Figs. 6 and 7 I have illustrated an alternative carrier R which may be of wood in which a longitudinal groove is cut to receive the spindles C, pins R¹ being provided 30 to engage the said screw threads.

Figs. 8, 9 and 10 illustrate stamped metal or compressed fibre or other guides S which may be used in place of pulleys M. Ribs S¹ are provided to lessen friction with the band 35 L, and a guide flange S² is provided. Pierced lugs S³ furnish means for attaching the guides by screws or otherwise, to the bottom of the box.

A pivoted "starting gate" T is provided to 40 restrain the "pieces" until released by raising the gate T by means of the handle T¹, the "pieces" all starting together. Winning posts U and V which may be foldable into 45 slots in the top of the box are mounted on opposite sides of the latter.

In operation the "pieces" are moved back to starting position either by lifting said "pieces" to raise carriers N clear of the spindles C, or by rotating the crank F in the 50 reverse direction. The "starting gate" T is then lowered in front of the "pieces" and the crank turned in the forward direction. Gate T is raised when desired and the crank turned continuously until one or other

"piece" has passed the winning posts, the 55 "pieces" passing and repassing one another as one or other is intercepted by the endless band, the effect of an actual race being vividly presented.

The specific apparatus illustrated in the 60 drawings is obviously capable of many constructional modifications within the spirit and scope of the invention.

What I claim is:

1. In a race game, a plurality of propelling members adapted for continuous operation, a plurality of game pieces, independent coupling means between the game pieces and the propelling members for advancing the game pieces, and variably operable uncoupling means for independently disconnecting the game pieces from the propelling members. 65

2. In a race game, a plurality of propelling members adapted for continuous operation, a plurality of game pieces, independent frictional coupling means between the game pieces and the propelling members for advancing the game pieces, and variably operable means for causing said frictional coupling means to slip for independently arresting the advancement of the game pieces by the propelling members. 70

3. In a race game, a plurality of members adapted for continuous operation, game pieces, yieldable coupling means for connecting the game pieces to the members, and chance operated means for holding the game pieces from advancement, said coupling means including relatively displaceable parts adapted to be moved one upon the other when said advancement is arrested for causing rocking of the game pieces. 85

4. In a race game, a plurality of propelling screws each having a spiral thread member thereon, a game piece for each screw, a carriage for each game piece adapted to straddle the respective screw and having a coupling lug for engagement between the convolutions of the spiral thread member to engage the latter and advance the game piece when the screw is turned, and means operable by chance for arresting advancement of the game piece, said lug being adapted to bind against the spiral thread and be raised thereby to rock the carriage and the game piece when advancement is arrested. 95

JOHN CARLISLE POMEROY MAGWOOD. 100
